United States Patent [19]

Kline et al.

[11] Patent Number: Des. 289,294

[45] Date of Patent: ** Apr. 14, 1987

[54] INTERFACE HOUSING FOR DATA PROCESSING SYSTEM

[75] Inventors: Jeffrey L. Kline; Stanley E. Koprowski, both of Austin, Tex.

[73] Assignee: International Business Machines Corporation, Armonk, N.Y.

[**] Term: 14 Years

[21] Appl. No.: 614,936

[22] Filed: May 29, 1984

[52] U.S. Cl. D14/114

[58] Field of Search 174/50, 52; D14/100, D14/107, 114; D13/40, 41; 361/331, 380, 390, 391, 392, 394

[57] CLAIM

The ornamental design for an interface housing for data processing system, substantially as shown and described.

DESCRIPTION

FIG. 1 is a top, front perspective view of the interface housing for data processing system showing my new design;

FIG. 2 is a rear view thereof;

FIG. 3 is a bottom, front and right side perspective view thereof;

FIG. 4 is a top, rear and left side perspective view thereof;

FIG. 5 is top, front and right side perspective view thereof, the cover on the top being in the open position.

FIG. 1

FIG. 2

FIG. 3

FIG. 4

FIG. 5
